CASTING MACHINE

Max Hummel, New York, N. Y.

Application July 25, 1945, Serial No. 607,076

4 Claims. (Cl. 18—26)

(Granted under the act of March 3, 1883, as amended April 30, 1928; 370 O. G. 757)

1

This invention relates to a casting machine, particularly useful in casting elongated articles of relatively low melting material, such as plastics or low melting metal.

It is an object of this invention to provide a machine for casting elongated articles such as metal rods with a minimum of handling and manipulation.

Another object of this invention is to provide a rod casting machine in which the product is ejected by pneumatic pressure and automatically directed to a receiving bin.

Still another object of this invention is to provide a rod casting machine in which the mold is integral and water jacketed.

Further objects and advantages of this invention, as well as its construction, arrangement and operation, will be apparent from the following description and claims in connection with the accompanying drawing, in which,

Figure 1 is a plan view of the machine of this invention, and

Figure 2 is a sectional elevation through the machine of this invention, taken along the line 2—2 of Figure 1.

Referring to the drawing in detail, the machine comprises an air cylinder 11, fixedly mounted on a base plate 12. Air cylinder 11 is provided with an outer flange 13 at its upper end, to which is bolted or similarly affixed a water jacket 14. The end plate of water jacket 14 is provided with a centrally located hole, which is counterbored to provide a shoulder, upon which rests packing ring 15.

An integral, annular mold 16 extends through but not beyond the end plate of water jacket 14, a shoulder near the end of mold 16 bearing upon packing ring 15. Mold 16 extends to the upper end of water jacket 14, and upon a shoulder at its upper end rests packing ring 17. Mold 16 is positioned and retained within water jacket 14 by closure plate 18, which is in threaded engagement with the interior of the upper end of water jacket 14. Closure plate 18 may be tightened by means of a spanner wrench or similar means so that pressure upon packing rings 15 and 17 will result in a watertight compartment in the interior of water jacket 14. Cooling water may be circulated through the interior of water jacket 14 by means of inlet opening 19 and outlet opening 20.

Positioned within air cylinder 11 is a piston 21 and a piston rod 22. In the down position, piston 21 is held slightly above the bottom of air cylinder 11 by piston rod 22, the lower end of which rests upon stop 23, extending from base

2

plate 12. The upper end of piston rod 22 extends a short way into the bore of mold 16. An annular weight 24, preferably of lead, encircles piston rod 22 and rests upon piston 21. An air inlet opening 25 enters air cylinder 11 near its bottom, and an air exhaust opening 26 is provided in air cylinder 11 near its top.

A shock plate 27 is positioned directly above the bore of mold 16, and is provided with a deflector plate 28. The shock plate and deflector plate assembly are pivotally mounted on pin 29, which is supported above the casting machine by strut 30. Stop 31 spaces deflector plate 28 from strut 30 so that shock plate 27 will normally be held in approximately horizontal position.

A tray 32 extends from the top of water jacket 14, and is mounted on the side opposite strut 30 by means of hinge 33. Tray 32 is illustrated as resting upon an upper edge of a receptacle or bin 34.

The operation of the machine is as follows. Cooling water is caused to circulate through water jacket 14 by means of inlet opening 19 and outlet opening 20. Next, molten metal is poured into the bore of mold 16 until the mold is filled. The upper end of piston rod 22, it will be noted, fills the bottom end of mold 16. Because of the cooling water surrounding mold 16, the molten metal solidifies quickly, whereupon a supply of compressed air is admitted to air cylinder 11 through air inlet opening 25.

The supply of air cylinder 11 is preferably controlled by a foot operated three-way valve (not shown), by means of which air inlet opening 25 is opened to a source of compressed air when the valve treadle is depressed, and opened to an exhaust port when the pressure on the valve treadle is removed. Such a valve is described in my co-pending application Serial No. 607,075, filed July 25, 1945.

The admission of compressed air to cylinder 11 under piston 21 causes piston 21 and piston rod 22 to rise until weight 24 strikes the end plate of water jacket 14. In so doing, piston rod 22 frees the cast rod from mold 16 and impels it completely out of the machine. The bore of mold 16 is preferably tapered, the diameter increasing from bottom to top, so that no difficulty is experienced in loosening and expelling molded rods. Mold 16 may be made of any material capable of withstanding the heat and any corrosive action of the molten metal to be cast, cast iron being a suitable material for casting zinc. Air exhaust opening 26 opens that portion of cylinder 11 above piston 21 to the atmosphere, so that no

high pressure cushion or vacuum may form above piston 21 and thereby impede its free movement.

When the cast rod has been impelled completely out of the casting machine, its upper end strikes shock plate 27. The shock plate and deflector plate assembly is caused thereby to pivot about pin 29, whereupon the lower end of deflector plate 28 strikes the lower end of the cast rod, impelling the rod into tray 32. If the outer end of tray 32 is lower than the inner end, the rod will slide unassisted down tray 32 into bin 34. The shock plate and deflector plate assembly will return to normal position, with deflector plate 28 resting against stop 31.

When the cast rod has been expelled from the machine, that portion of air cylinder 11 below piston 21 is allowed to exhaust to the atmosphere, as by releasing the treadle of the three-way valve above described, and piston 21 and piston rod 22 will return to their normal down position, assisted in the return stroke by weight 24.

It will be apparent that the machine of this invention will enable a simple operator to cast large numbers of rods at a high rate of speed, it being necessary only to pour molten metal into the mold, and then operate the ejecting mechanism, by foot treadle or otherwise. The operator need at no time handle hot molds or rods, the rods being ejected and delivered to a bin automatically. Nor is it necessary that any time be lost cooling molds or product, since the mold is constantly cooled and the product may safely be delivered hot.

The machine, it will be apparent, is easily adaptable to cast rods of varying sizes and lengths. Mold 16 may be readily removed and changed to a mold of different diameter by removing closure plate 18, and piston rod 22 may be removed and replaced by unbolting water jacket 14 from air cylinder 11.

It is to be understood that various modifications and changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A machine for casting elongated articles

comprising a mold, a piston rod positioned at one end of said mold, means for driving said piston rod through said mold, whereby elongated cast articles may be ejected from said mold, and a shock plate and deflector plate assembly pivotally mounted above said mold, said assembly being so arranged and positioned that an ejected article will contact said shock plate and cause pivotal movement of said deflector plate toward one side of said machine.

2. A machine for casting elongated articles comprising a mold, a piston rod positioned at one end of said mold, means for driving said piston rod through said mold, whereby elongated cast articles may be ejected from said mold, a shock plate and deflector plate assembly pivotally mounted above said mold, said assembly being so arranged and positioned that an ejected article will contact said shock plate and cause pivotal movement of said deflector plate toward one side of said machine, and a tray projecting from that side of the machine toward which said deflector plate may pivotally move.

3. A machine for casting elongated articles comprising a cylinder having an open end, a mold secured to the open end of said cylinder, a piston within said cylinder, a piston rod extending from said piston into said mold, whereby elongated cast articles may be ejected from said mold by movement of said piston and piston rod, a shock plate and deflector plate assembly pivotally mounted above said mold, said assembly being so arranged and positioned that an ejected rod will contact said shock plate and cause pivotal movement of said deflector plate toward one side of said machine, and a tray projecting from that side of the machine toward which said deflector plate may pivotally move.

4. A machine for casting elongated articles comprising an elongated mold, an article ejector associated with said mold, means for moving said ejector longitudinally within said mold, and an article deflector of bell crank form pivotally mounted adjacent said mold, said deflector having a shock arm disposed in the path of articles ejected from said mold and a deflector arm extending toward said mold adjacent said path whereby the impact of the ejected articles against said shock arm swings said deflector arm into deflecting engagement with said articles.
